UNITED STATES PATENT OFFICE.

ARTHUR L. BREITENSTEIN, OF AKRON, OHIO, ASSIGNOR TO THE LANCASTER TIRE & RUBBER COMPANY, OF LANCASTER, OHIO, A CORPORATION OF OHIO.

DESIGN FOR A TIRE-TREAD.

50,265.

Specification for Design.

Patented Feb. 6, 1917.

Application filed November 16, 1916. Serial No. 131,805. Term of patent 7 years.

To all whom it may concern:

Be it known that I, ARTHUR L. BREITENSTEIN, a citizen of the United States, residing at Akron, in the county of Summit and State of Ohio, have invented a new, original, and ornamental Design for Tire-Treads, of which the following is a specification, reference being had to the accompanying drawings, forming part thereof.

Figure 1 is a face view showing my newly designed tire tread, and,

Fig. 2 is a transverse section of the same on line 2—2 of Fig. 1.

I claim:

The ornamental design for a tire tread, as shown.

ARTHUR L. BREITENSTEIN.

Witnesses:

W. E. WILSON,
A. FLEITER.
